Inventor:
Allan B. Hendricks, Jr.,
by *John J. Davis*
His Attorney.

UNITED STATES PATENT OFFICE.

AILLAN B. HENDRICKS, JR., OF PITTSFIELD, MASSACHUSETTS, ASSIGNOR TO GENERAL ELECTRIC COMPANY, A CORPORATION OF NEW YORK.

STATIONARY INDUCTION APPARATUS.

Application filed August 2, 1921. Serial No. 488,339.

To all whom it may concern:

Be it known that I, AILLAN B. HENDRICKS, Jr., a citizen of the United States, residing at Pittsfield, county of Berkshire, State of Massachusetts, have invented certain new and useful Improvements in Stationary Induction Apparatus, of which the following is a specification.

My invention relates to stationary induction apparatus and has for its general object an improved construction and arrangement of parts.

More particularly my invention relates to apparatus of this type which is designed for high voltage service; for example in the service required when it is desired to transform from one high voltage to another as for instance where a "tie-in" transformer is required.

In designing apparatus of this character it is very difficult to place the primary and secondary transformer windings in sufficiently close inductive relation to reduce the reactance to a satisfactory low value on account of the large electrical clearances required between the primary and secondary windings for insulating purposes.

In the practice of my invention I am able to accomplish the desired reduction in the reactance in such transformers by keeping the primary and secondary windings grouped together but separate from one another, by disposing them on separate parts of the same core and coupling them magnetically or inductively by means of a third winding which I have here styled a coupling tertiary.

For a more complete understanding of the nature and objects of my invention reference should be had to the following detailed description when taken in connection with the accompanying drawing in which:

Fig. 1 shows, partly in elevation and partly in section, a transformer constructed in accordance with my invention; while Fig. 2 is an explanatory diagram.

Referring now to the drawing and particularly to Fig. 1, 10 denotes a magnetic core of the three legged shell type, about the central or winding leg 11 of which are disposed the windings. Here the upper outside group 12 will be considered the primary winding or that which receives energy from the supply circuit, while the lower group

13 may be similarly considered the secondary or the one which supplies energy to the circuit fed by the transformer.

The coupling tertiary winding is shown at 15, and comprises the two sections 15^a and 15^b which are arranged in close inductive relation with the primary and secondary windings 12 and 13 respectively. The sections 15^a and 15^b are provided with the same number of turns and are connected by conductors 16 in opposition to each other so that when the voltages induced therein are equal no circulating current flows through them. The sections 15^a and 15^b act to neutralize the leakage fluxes of the main and secondary windings 12 and 13 so as to maintain the same amount of main flux through both the primary and secondary windings. Since the secondary leakage flux tends to decrease the amount of main flux linking the secondary winding, the voltage induced in the section 15^b of the tertiary coupling winding 15 is less than that induced in the section 15^a consequently a circulating current will flow through the two sections of the tertiary winding which will tend to neutralize the leakage flux, and maintain the same amount of main flux through each section thereby reducing the reactance between the primary and secondary windings.

If so desired an independent circuit 17 may be connected to the connection between the two sections 15^a and 15^b so as to supply power therefrom or receive power therefrom. With reference to this independent circuit the sections are connected in parallel where-as when they are considered by themselves they are connected in series and in opposition to each other. In this way three independent circuits 17, 18 and 19 may be tied together by one transformer as indicated in Fig. 2.

The operation of my invention will be more clearly understood from a consideration of Fig. 2.

Here P denotes the primary, S the secondary, and *a* and *b* their respective sections of the coupling tertiary. The sections *a* and *b* are indicated as connected in series. As a result the E. M. F.'s, whose directions in these windings are symbolically indicated by arrows adjacent each one respectively, are seen to be related to each other as though two transformers were connected in cascade

relation; i. e. the E. M. F. in the section at *a* is opposed to that in the winding at *P*; and again the induced E. M. F. at *a* produces, as a consequence of the tertiary current which flows, an equal and opposite counter E. M. F. in the winding at *b*, the latter in turn inducing an opposing E. M. F. in the secondary at *S*. While the ratio of transformation for the windings *P* and *S* may be small and consequently may require relatively great electrical clearance between these windings, the ratio of transformation between each of these windings and the tertiary may be more or less arbitrarily chosen and made as large as is desired in order to secure as close coupling magnetically between them and the tertiary as may be feasible. Such an arrangement is equivalent to connecting the windings *P* and *S* in cascade by means of step-down and step-up transformers.

It is perceived, however, that to couple the primary and secondary windings in one transformer, as I have described, very greatly reduces the cost of the necessary apparatus and at the same time provides means for suppressing the leakage flux in a manner such that mechanically the windings may not be closely related but in effect magnetically they are closely coupled.

While I have shown and described my invention in connection with a single phase shell type transformer it is obvious to one skilled in the art that my invention is applicable to other types of transformers such as polyphase and core type transformers.

Having now described an embodiment of my invention which is at present the best means known to me for carrying the same into effect, I would have it understood that this is merely illustrative, and that I do not mean to be limited thereby to the precise details shown nor restricted in the choice of

recognized equivalents except as defined in my claims hereunto annexed.

What I claim as new and desire to secure by Letters Patent of the United States, is:—

1. In stationary induction apparatus, the combination with a core, of primary and secondary windings disposed respectively on separate portions thereof, and a tertiary coupling winding coupled closely magnetically with both said primary and said secondary.

2. In stationary induction apparatus, the combination with a core, of primary and secondary windings disposed respectively on separate portions thereof, and a tertiary coupling winding composed of sections associated respectively with said primary and said secondary and coupled closely magnetically therewith.

3. In stationary induction apparatus, the combination with a core, of primary and secondary windings disposed respectively on separate portions thereof, and sections of a third winding associated respectively with said primary and said secondary, said sections being connected in series and closely coupled magnetically with their respective windings.

4. In stationary induction apparatus, the combination with a core, of primary and secondary windings disposed respectively on separate portions thereof, and sections of a third winding disposed along the core so as substantially to envelop the same magnetically, said sections being associated respectively with said primary and secondary windings and being connected in series with each other, and each of said sections being coupled closely magnetically with its associated winding.

In witness whereof, I have hereunto set my hand this 29th day of July, 1921.

ALLAN B. HENDRICKS, Jr.
